UNITED STATES PATENT OFFICE.

JOHN PETERSON, OF MINNEAPOLIS, MINNESOTA.

DESIGN FOR A MENU-HOLDER.

48,079.

Specification for Design.

Patented Nov. 2, 1915.

Application filed July 3, 1915. Serial No. 37,972. Term of patent 3½ years.

To all whom it may concern:

Be it known that I, JOHN PETERSON, a citizen of the United States, residing at Minneapolis, in the county of Hennepin and State of Minnesota, have invented a new, original, and ornamental Design for Menu-Holders, of which the following is a specification, reference being had to the accompanying drawing, forming part thereof.

The figure is a perspective view of a menu holder, showing my new design.

I claim:

The ornamental design for a menu holder, as shown.

JOHN PETERSON.

Witnesses:

EVA E. KÖNIG,
HARRY D. KILGORE.
